UNITED STATES PATENT OFFICE.

CALVIN J. WALTERS, OF SAN ANGELO, TEXAS.

WATER HEATER.

Application filed March 21, 1924. Serial No. 700,909.

To all whom it may concern:

Be it known that I, CALVIN J. WALTERS, a citizen of the United States, residing at San Angelo, in the county of Tom Green and State of Texas, have invented certain new and useful Improvements in Water Heaters, of which the following is a specification.

This invention relates to new and useful improvements in water heaters and has for its principal object to provide a simple and efficient means whereby a supply of hot water will at all times be had after the water which is initially in the water tank has been heated, means being provided for automatically supplying water to the tank simultaneously with the discharging of the water in the tank below a predetermined level.

A further object of the invention is to provide a water heater of the above mentioned character, wherein the water inlet pipe is provided with a coiled section disposed above the heater so that the water passing therethrough will be heated previous to the same being supplied to the water tank thus assuring a supply of hot water within the tank.

A still further object of the invention is to provide a water heater of the above mentioned character wherein means is provided with the water tank for permitting the escape of steam which may be generated in the top thereof thus preventing any possibility of any damage occurring.

A still further object of the invention is to provide a water heater of the above mentioned character which is simple in construction, inexpensive, strong and durable, and furthermore adapted for the purposes for which it is designated.

Other objects and advantages of this invention will become apparent in the course of the following description.

In the accompanying drawings forming a part of the specification and in which like numerals designate like parts throughout the application,

Figure 1 is a side elevation with parts in section of my improved water heater,

Figure 2 is a top plan view of the water tank, and

Figure 3 is a sectional fragmentary view of the closure for the water tank.

In the drawing, where for the purpose of illustration is shown a preferred embodiment of my invention, the numeral 1 designates a substantially cylindrical casing of a

stove wherein the grate 2 is arranged in the bottom of the casing, access being had thereto by means of the door 3, the base 4 for the casing 1 being of any conventional construction and having provided therein the usual ash pan for the purposes well known in the art. Suitable legs such as are shown at 5 in the drawing are provided on the base for holding the stove and casing above the floor A.

Supported in the upper portion of a cylindrical casing 1 in any suitable manner is the water tank designated by the numeral 5^a. The top of the water tank is preferably open and is provided with the inwardly extending annular flange 6 upon which is adapted to be secured the removable cover 7 by means of the thumb nuts and bolts 8 in the manner clearly shown in Figure 3 of the drawing, a suitable gasket preferably formed of asbestos being interposed between the flange 6 and the cover 7 and is designated by the numeral 9 in the drawing.

Extending upwardly through the base 4 and the casing 1 supported thereon is the water supply pipe 10. The pipe 10 is adapted to be communicated with any suitable source of supply (not shown) and the upper portion of the supply pipe which extends within the casing 1 is provided with the coiled section 11, the latter being arranged substantially in a horizontal plane directly below the bottom of the water tank 5^a and having the end thereof directed upwardly into communication with the bottom of the water tank in the manner clearly shown in the drawing. This supply pipe 10 provides a means whereby cold water may be supplied from a suitable source to the water tank 5 in the manner as will be hereinafter more fully described.

Provided adjacent the top of the water tank 5^a is the water outlet pipe 12. A suitable coupling such as is shown at 13 may be provided in connection with the outlet pipe 12 whereby a pipe 14^a may extend downwardly through the casing 1 and through the base 4, and through the floor A and is adapted to be connected to the faucet 14 in the bath room or any desirable place. A suitable faucet 14 is mounted on the extension of the outlet pipe 12 which extends through the upper portion of the casing 1 in the manner shown in Figure 1 of the drawing.

For the purpose of regulating the supply

of cold water to the water tank 5^a, I provide a valve 15 in the water supply pipe 10 and connected thereto by means of the elongated rod or lever 16 which extends upwardly in the casing 1 between the outer wall of the water tank and the inner wall of the casing, is the float 17. The float 17 is supported by means of the rods 18 within the upper portion of the water tank and the upper end of the rod 18 is connected to the upper end of the lever 16 by means of the link 19 which is pivotally supported intermediate its ends in the bracket 20, the latter being carried by the under side of the cover 21 provided for the top of the cylindrical casing 1. The float 17 rests on the surface of the water contained in the water tank, and normally when the water in the tank is at the level indicated in the drawing, the valve 15 will be closed. When the stove is in operation, the water in the tank will be caused to be heated as will also the water contained in the coil section 11 which is disposed directly above the fire. As the water is drawn off from the top of the tank to the outlet pipe 12, the float 17 will descend simultaneously with the fall of the water in the tank and will simultaneously actuate the lever 16 through the medium of the rod 18 and link 19 so as to open the valve 15 and thus cause the water in the supply pipe 10 to be delivered to the coil section 11 where the same will be heated previous to the delivery thereof into the bottom of the tank. When the water again rises in the tank 5 to the level shown in Figure 1, the float 17 will also rise simultaneously therewith and thus shut off a further supply of water to the tank. In this manner, a continuous supply of hot water may be obtained from the tank and will simultaneously cause the water to be supplied to the bottom of the tank in a heated state thus preventing the loss of considerable time in waiting for the water in the tank to become heated as is now the case with the water heaters and oil tanks now in use.

For the purpose of permitting any steam which may be generated in the top of the water tank to escape therefrom, I provide the removable closure 7 with an outlet pipe 22 which extends upwardly through the

collar 23 provided on the cover 21 for the casing 1 and the upper end of the pipe 22 will be disposed within the flue pipe 24 supported on the cover 21, in the manner clearly shown in the drawing. A suitable damper such as illustrated at 25 is provided in the flue pipe 24 and any suitable means may be provided therefor for actuating the same as may be desirable.

The simplicity of my device will thus provide a constant supply of hot water, and the simplicity in which the several parts operate will enable the same to efficiently and positively insure the supply of water to the tank simultaneously with the discharging of the hot water therefrom. A device of this character may not only be manufactured at a very low cost but will also be strong and durable.

While I have shown a preferred embodiment of my invention, it is to be understood that various changes in the size, shape and arrangement of parts may be resorted to without departing from the spirit of the invention and the scope of the appended claim.

Having thus described the invention, what I claim is:

A water heater for domestic purposes comprising a vertically elongated heat confining casing, heating means arranged in said casing at the bottom thereof, a water tank supported in the upper portion of the casing above said heating means, said tank being provided at its top with a removable cover, a water supply pipe extending upwardly through the casing and adapted to be connected to the bottom of said water tank, said supply pipe having a horizontally disposed substantially flat heating coil formed therein and disposed in spaced parallelism below the bottom of said tank, a float in said tank having its stem extending slidably through an opening in said cover, a lever mounted for rocking movement in said casing and connected at one end to said float stem, a cut off valve in said water supply pipe, a link connection between said valve and the other end of said lever, and a water delivery pipe leading from the top portion of said tank.

In testimony whereof I affix my signature.
CALVIN J. WALTERS.
